UNITED STATES PATENT OFFICE.

PATRICK SHEA, OF CHICAGO, ILLINOIS.

LINOTYPE-MACHINE ATTACHMENT.

SPECIFICATION forming part of Letters Patent No. 758,284, dated April 26, 1904.

Application filed May 4, 1903. Serial No. 155,531. (No model.)

To all whom it may concern:

Be it known that I, PATRICK SHEA, a citizen of the United States, residing at Chicago, in the county of Cook and State of Illinois, have 5 invented a new and useful Improvement in Linotype-Machine Attachments, of which the following is a specification.

My invention relates particularly to the actuating means of the assembler-block, sometimes termed "assembling-elevator," of linotype-machines of the general construction set forth in Mergenthaler's patent, No. 557,000, dated March 24, 1896.

My primary object is to provide knee-operated mechanism for raising the assembler-block at which the composition takes place, so that it will be unnecessary for the operator to employ his hands for such purpose.

My invention is illustrated in its preferred embodiments in the accompanying drawings, in which

Figure 1 represents a perspective view of a portion of a linotype-machine provided with my improvement, and Fig. 2 a sectional view 25 illustrating a modification of my improved device.

In the preferred construction A represents the keyboard of a machine of the type described in the above-mentioned patent; B, a vertically - reciprocable assembler-block whereat the letter-matrices are first aligned as the composition proceeds; C, a link connected with the member B in the usual manner and through the medium whereof said member is elevated; C', the usual rock-shaft journaled in suitable bearings α and equipped at one end with a handle C² and at the opposite end with an arm C³, pivotally connected at its rear end with the lower end of the link C; and D, my improved knee-actuated device connected with the arm C³.

In the form shown in Fig. 1 the device D comprises a member b, adjustably clamped upon the arm C³, a link b' of adjustable length, 45 and a yoke or curved knee-engaging member b². The member b comprises a bar having a long slot which receives the arm C³ and a clamping-screw c. The lower end of the member is slotted to receive the link b', with which it is connected by a pivot c'. The link b' com-

prises an upper internally-threaded portion d, a lower internally-threaded member d', and a right and left threaded connecting-rod d². The member b² has a short stem equipped with a slotted head f, in which the lower end of the link b' is held by a pivot f'. The portion d' of the link b' has lugs or stops f², f³, which limit the swinging motion of the link b' with relation to the member b².

In the modification shown in Fig. 2 g, g', g² represent portions of a link corresponding with the portions d, d', d² of the link b', and h represents a yoke corresponding with the yoke b². In this construction the transverse pivotal connection between the link and yoke is dispensed with and the yoke has vertical swivel connection with the link. The yoke is of convex cross-section at its lower surface, which permits it to rock upon the knee or thigh of the operator.

In Fig. 1 the device is represented in the position it would occupy were it resting upon the operator's knee.

In attaching the device to the arm C³ the clamp b is set so as to incline rearwardly and upwardly. When it is desired to elevate the assembler-block, which heretofore has been accomplished by depressing the handle C², the knee of the operator is raised, lifting the arm C³ through the medium of the link b' and clamp b. As the arm C³ rotates about its shaft C¹ the clamp is brought to a vertical position, straightening the joint at its lower end and increasing the distance between the knee and the arm C³. Thus for a given movement of the knee a greater movement of the arm C³ is effected. Either one of the stops f², f³ may serve in the operation, according to the convenience of the operator, his stature, &c. Moreover, a certain slight movement between the link and yoke may take place as the joint at c' straightens, reducing the rocking movement of the yoke upon the knee.

In the modification of Fig. 2 the yoke is of a configuration which permits it to rock freely upon the knee, and its swivel connection with the link permits the yoke to accommodate itself to the leg, regardless of the angle which the latter occupies with reference to the front of the machine.

The clamp of the device may be adjusted forwardly or backwardly and angularly to accommodate the device to persons of different stature.

5 Changes in details of construction are contemplated, so that no undue limitation should be understood from the foregoing detailed description.

What I regard as new, and desire to secure

10 by Letters Patent, is—

1. The combination with the assembler-block, and the upwardly-swinging rock-arm for elevating the same in a linotype-machine, of an actuating device, comprising a clamp secured to said arm, and a knee-engaging member equipped with a stem pivotally joined to said clamp, for the purpose set forth.

15 2. An actuating device for the purpose set

forth, comprising a clamp for engaging the rock-arm linked to the assembler-block, and a rod joined thereto by a transverse pivot and equipped at its lower end with a curved knee-engaging member.

3. An actuating device for the purpose set forth, comprising a clamp for the rock-arm 25 described; a link joined thereto by a transverse pivot, a curved knee-engaging member joined to said link by a transverse pivot, and stops for limiting the relative movements between said link and said knee-engag- 30 ing member.

PATRICK SHEA.

In presence of—

A. C. KITTLESON,

WALTER N. WINBERG.
